UNITED STATES PATENT OFFICE

2,613,904

ANGLE POST AND SHORING HEAD

Takeo Sato, Honolulu, Territory of Hawaii

Application August 26, 1948, Serial No. 46,327

1 Claim. (Cl. 248—354)

1

This invention relates to adjustable columns used in shoring and other construction work wherein it is desirable to adjust the height of supporting posts and parts thereof, and in particular the invention includes a post formed with two pairs of oppositely positioned angles with the legs of the angles in two crossed planes, one plane being at an angle of 90° in relation to the other, and with one pair of angles slidable over the other.

The invention also includes a shoring head with means for adjustably mounting the shoring head on the post and means for adjustably mounting beam forming elements on the shoring head.

The purpose of this invention is to provide a portable post for use in shoring and concrete form work that may be taken down after use and reused in which the height thereof may readily be adjusted.

In shoring up under concrete floors and beams wood posts are generally used and cross members are nailed or bolted to the upper ends and when it is desired to change the elevation blocks are driven in under the lower ends. With props of this type it is difficult to maintain a continuous level, and when they are knocked down very few of the posts are suitable for reuse. With this thought in mind this invention contemplates a post formed with pairs of angles with one pair slidable over the other and with the angles held by studs and keys in continuous rows of bolt holes, and with a head having outwardly extending arms carried by the upper ends of the angles, wherein all of the parts are adjustable and adapted for reuse.

The object of this invention is, therefore, to provide means for forming extensible shoring posts with angle bars wherein one pair of angle bars is slidable over another and the bars are held in selected positions by studs.

Another object of the invention is to provide means for adjustably mounting a shoring head on a pair of angles with the angles positioned back to back or in the form of a star.

Another object of the invention is to provide means for mounting a head on one end and a base on the other of a post formed of angle bars with the bars in telescoping relation.

A further object of the invention is to provide a shoring post having a head and a base that is formed with pairs of angle bars in telescoping relation which is of a simple and economical construction.

With these and other objects and advantages in view the invention consists of the new and useful combination, construction, and arrangement of parts as hereinafter more fully described, set forth in the claim appended hereto, and disclosed in the accompanying drawings forming part hereof, wherein:

Figure 1 is a view illustrating an adjustable

2

post having a shoring head and with a beam form carried by the head.

Figure 2 is a longitudinal section through the shoring head showing the head on the upper end of a post with the lower part of the post broken away.

Figure 3 is a plan view of the shoring head with the post and mounting elements shown therein, taken on line 3—3 of Figure 2.

Figure 4 is a cross section taken on line 4—4 of Figure 2 showing the shoring head with the upper end of the post therein and with parts of the post broken away.

Figure 5 is a plan view of the shoring head.

Figure 6 is a detail showing one of the lockers for securing the shoring head to the upper end of the post.

Figure 7 is a side view of part of a post showing an angle locker for holding the angles of the post at intermediate points, with the locker shown in dotted lines.

Figure 8 is a cross section through the angle post and locker taken on line 8—8 of Figure 7.

Figure 9 is a vertical section taken on line 9—9 of Figure 8.

Figure 10 is a cross section through the post taken on line 10—10 of Figure 11 showing the pairs of angles with the locking studs and keys, said section also being taken on Figure 1.

Figure 11 is an elevational view of the post taken on line 11—11 of Figure 10 with parts broken away.

Figure 12 is an elevational view showing a wood beam connector at the upper end of the post with the parts separated.

Figure 13 is a view showing a side elevation of the connector illustrated in Figure 12 with the beam shown in section.

Figure 14 is a detail illustrating one of the studs and locking keys used for holding the legs of the angles together.

Figure 15 is a view showing a side elevation of the shoring head mounted on a wood post, with the lower part of the post broken away.

Figure 16 is a vertical cross section taken on line 16—16 of Figure 15 showing the locking bolts.

Figure 17 is a sectional plan through the post and shoring head taken on line 17—17 of Figure 16.

Figure 18 is a detail showing a washer adapted to be used on the locking bolts shown in Figure 16.

Figure 19 is a detail showing the U-shaped heads and locking keys of the bolts shown in Figure 16.

Figure 20 is a side elevational view similar to that shown in Figure 1 illustrating the shoring head on a wood post and supporting beam forms.

Figure 21 is a view illustrating a base adapted to be mounted on the lower end of the post.

Figure 22 is a sectional plan through a post

showing the post mounted on the base shown in Figure 21.

Figure 23 is a detail showing one of the lockers for holding the angles of the posts at intermediate points, as illustrated in Figure 7.

Referring now to the drawings wherein like reference characters denote corresponding parts the improved angle post and shoring head of this invention include a lower pair of angles 10 and 11, an upper pair of angles 12 and 13, a head 14, a base 15, and studs 16 having slots 17 therein and keys 18.

The base 15 is provided with clip angles 19 and 20 which are secured thereto by welding and the legs of the angles are provided with bolt holes 21 and 22 respectively, by which the lower angles 10 and 11 are secured to the base by the studs 16 and keys 18. The angles 10 and 11 are secured at intermediate points by lockers 23 as shown in Figures 7 and 23 with the lockers held between the legs of the angles by the studs and keys as shown in Figure 8. The upper angles 12 and 13 which are also held by lockers 23 with studs 16 and keys 18, are adapted to slide over the angles 10 and 11, with the flat surfaces of the legs of the angles in sliding engagement, and these angles are secured to the lower angles 12 and 13 in selected positions by the studs 16 and keys 18.

The shoring head 14 is also secured to the upper ends of the upper angles 12 and 13 by the studs 16 and keys 18, and the head is held in position by lockers 24, as illustrated in Figure 6, the lockers having V-shaped sides formed by plates 25 and 26 that fit between the legs of the angles. The plates 25 and 26 and also the ends 27 and 28 of the lockers are provided with bolt holes 29 by which they are held in position by the studs 16 and keys 18. The shoring head is U-shape in cross section having an upper plate 30 with side plates 31 and 32 and the side plates are provided with inclined lower edges sloping upwardly from a lower edge 33 to ends 34 and 35, and the ends are provided with transverse plates 36 and 37. The head is also provided with intermediate webs 38 and 39 and a centrally disposed reinforcing section 40 that has a plate 41 which rests upon the upper end of the post. The upper plate 30 is provided with groups of bolt holes 42 and 43 in the opposite sides and the side plates 31 and 32 are provided with groups of openings 44 and 45 adjacent the ends and 46 in the central parts, and as illustrated in Figures 1 and 20, beam forms may be attached to the shoring heads by the studs through the openings 44 and 45, and the heads may be attached to the posts through the openings 46.

For some uses it is desired to use a wood beam at the upper end of the post, or attach the post to a wood beam and with this thought in mind the device includes a plate 47 having a flange 48 at one side with nail holes 49 therein and provided with clip angles 50 similar to the angles 19 and 20 on the base 15, on the under surface. The angles 50 are provided with bolt holes 51 through which the device may be secured to the post by the studs 16 and keys 18 in order to locate the upper end of the post in relation to the beam 52.

In Figures 15 to 20, inclusive, the shoring head 14 is shown on a post 53 with the head secured in position on the post by bolts 54 having U-shaped ends 55 and, as shown in Figure 16 the bolts extend through holes 56 and 57

with the ends held in holes 58 and 59. The post 53 is provided with washers 60 which have openings 61 that register with the holes 58 and 59, and nail holes 62 by which they are held to the post by nails 63. Keys 64 are provided in the U-shaped ends of the bolts and the opposite ends are threaded and provided with nuts 65. The side plates 31 and 32 are also provided with small holes 66 through which the shoring head may be secured to wood posts by nails or the like.

With the parts arranged in this manner and with the bolt holes 67 and 68 in the legs of the angles 10 and 11, respectively, and 69 and 70 in the legs of the angles 12 and 13, respectively, properly spaced the height of the posts may be adjusted to accurately level a floor or beam and with the parts assembled in this manner it is only necessary to tap the keys to take the forms down. The forms and supports therefor may, therefore, be removed without damaging the parts so that they may be reused without repair.

The shoring head and angle post may be used directly under a concrete floor or the like, or as illustrated in Figures 1 and 20 they may be used to support a form framework, as indicated by the numeral 71 and this may be adjustably held by the supports 72 and 73 from the head 14 by the studs 16 and keys 18, as shown.

It will be understood that other modifications may be made in the design and arrangement of the parts without departing from the spirit of the invention.

What is claimed is:

In an adjustable column, a horizontally disposed base, a pair of opposed V-shaped clip angles secured to said base and provided with openings therein, a first pair of coacting angle bars connected to said clip angles and each having a V-shaped cross section, a second pair of coacting angle bars of V-shape cross section slidably engaging said first pair of angle bars, the angle bars of said first pair being arranged with their apices facing each other, and the angle bars of said second pair having their apices facing each other, there being a plurality of spaced registering openings in said angle bars, the openings being arranged in the sides of said angle bars, V-shaped locking members connecting the angle bars of said first pair together and connecting the angle bars of said second pair of angle bars together, studs extending through the registering openings in said angle bars, there being a slot arranged in each of said studs, a tapered wedge positioned in each of said slots in said studs, a shoring head detachably mounted on the upper ends of said second pair of angle bars.

TAKEO SATO.
